UNITED STATES PATENT OFFICE.

WILMER DUNBAR, OF GREENSBURG, PENNSYLVANIA, ASSIGNOR TO ALLEN TIRE & RUBBER COMPANY, OF ALLENTOWN, PENNSYLVANIA.

DESIGN FOR AN AUTOMOBILE-TIRE.

57,073.

Specification for Design.

Patented Feb. 8, 1921.

Application filed May 1, 1920. Serial No. 378,303. Term of patent 7 years.

To all whom it may concern:

Be it known that I, WILMER DUNBAR, a citizen of the United States, residing at Greensburg, in the county of Westmoreland and State of Pennsylvania, have invented a new, original, and ornamental Design for Automobile-Tires, of which the following is a specification.

Referring to the accompanying drawing forming a portion of this specification:

The figure is a fragmentary perspective

view of an automobile tire, showing my new design.

What I claim is:

The ornamental design for an automobile tire, as shown.

In testimony whereof I affix my signature.

WILMER DUNBAR.
